(57) **CLAIM**

The ornamental design for a lunch container, as shown, and described.

DESCRIPTION

FIG. 1 is a perspective view of a lunch container showing our new design, in a closed position;

FIG. 2 is a front elevation view of FIG. 1;

FIG. 3 is a rear elevation view of FIG. 1;

FIG. 4 is a left side elevation view of FIG. 1, the right side elevation view being a mirror image of FIG. 4;

FIG. 5 is a top plan view of FIG. 1;

FIG. 6 is a perspective view of the lunch container, in an open position; and

FIG. 7 is a front elevation view of FIG. 6;

FIG. 8 is a rear elevation view of FIG. 6;

FIG. 9 is a left side elevation view of FIG. 6, the right side elevation view being a mirror image of FIG. 9;

FIG. 10 is a top plan view of FIG. 6; and,

FIG. 11 is a bottom plan view of FIG. 6.

The broken lines in the drawings represent portions of the lunch container that form no part of the claimed design.

1 Claim, 11 Drawing Sheets
